United States Patent Office.

FREDERICK COLE, OF KANKAKEE, ILLINOIS.

Letters Patent No. 96,085, dated October 26, 1869.

PALLET AND BRUSH FOR GRAINING.

The Schedule referred to in these Letters Patent and making part of the same.

To all whom it may concern:

Be it known that I, FREDERICK COLE, of Kankakee, in the county of Kankakee, and State of Illinois, have invented a new and useful Improvement in Pallets and Brushes; and I do hereby declare that the following is a full, clear, and exact description thereof, which will enable those skilled in the art to make and use the same, reference being had to the accompanying drawings, and letters marked thereon, making a part of this specification, in which—

Figure 1 is a perspective representation of my improved pallet, with the brush in position for receiving different-colored paints, and

Figure 2, a sectional elevation of the same.

The object of the present invention is to provide suitable means for distributing evenly upon one brush different-colored paints, preparatory to painting, graining, &c., in ornamental style; and

Its nature consists of a pallet which is provided with a series of chambers, corresponding in number to the number of colors to be used in any particular case, in which chambers the various colors are placed, and gathered therefrom by a brush, which is so divided off into suitable sections, that each section will fall into its proper compartment. The back of said compartments being provided with a scraper, cleans the surplus paint from the brush, as the latter is drawn from the aforesaid pallet; and the divisions between the compartments, projecting upward at their ends, provide convenient means for placing the brush properly on the pallet, as the whole is hereinafter fully described.

A B C represent a box-pallet, which is made of

metal, or other suitable material, and which is divided off into a series of compartments, by means of partitions I I I, &c., in order that the various-colored paints used may be kept separate.

These partitions are made quite thin, and their ends at J J J, &c., project above the other parts, in order that every division of the brush S may be readily placed in its proper compartment.

A thin scraper, T, is also so placed in position over the back ends of the partitions, that when the brush is drawn out from the compartments, the surplus paint will be removed, and carried back into its respective place.

The brush, as will be seen in fig. 1, is divided off into several sections, corresponding in width to the width of the compartments in the pallet.

By means of this construction and arrangement, an artist is enabled to carry upon one brush all of the colors necessary to line or shade any ordinary mouldings, or to carry the requisite colors for graining walls, &c., whereby a very great saving is made, both in time and labor.

Having thus described my invention,

What I claim, and desire to secure by Letters Patent of the United States, is—

Distributing various colors on to a brush, S, provided with sections P, in combination with a pallet, A B C, provided with compartments I, to hold various-colored paints, as set forth.

FREDERICK COLE.
